UNITED STATES PATENT OFFICE.

FRED E. WHITE AND FREDERICK E. HOOPER, OF GARDNER, MASSACHUSETTS, ASSIGNEES TO CENTRAL OIL & GAS STOVE COMPANY, OF GARDNER, MASSACHUSETTS, A CORPORATION OF MASSACHUSETTS.

OIL-STOVE.

1,273,209.

Specification of Letters Patent. Patented July 23, 1913.

Application filed October 9, 1917. Serial No. 195,639.

To all whom it may concern:

Be it known that we, FRED E. WHITE and FREDERICK E. HOOPER, both of Gardner, Massachusetts, citizens of the United States of America, have invented certain new and useful Improvements in Oil-Stoves, of which the following is a specification.

Our invention relates to an oil burner of the type shown in Letters Patent 1,201,902 granted October 17, 1916, the present invention having to do with the particular construction of the air distributer which is adapted to be used with any form of locking means, either such as is shown in our patent referred to above, or in an application of even date herewith, having manually actuated locking means for limiting the upward movement of the wick, while allowing the removal of the distributor for the purpose of gaining access to the central draft tube.

Instead of utilizing, as in our issued patent, a wick stop loosely secured to the air spreader or distributer we provide a skirt *a* which fits within the inner wick tube *b*, the skirt being of such diameter as to leave an air space *c* between it and the inner wick tube and it is understood that this skirt may be provided with any known or improved means for limiting its upward movement and permitting detachment. The upper end of the skirt we flare out slightly, as shown at *d*, and provide this flared section with perforations *e*, these perforations being directly in line with the inner wall of the wick when the parts are in raised position. The metal is then flared outwardly in a horizontal direction as shown at *f* to form the wick stop, the flange resting directly upon the wick as shown. Instead of the protruding shoulder *e* of our former construction or the flanges shown in the patents of Berg 739,143 of September 15, 1903, or the British patent of Williams 21,734 of October 15, 1898, we extend the metal of the distributor upwardly on approximately the outer line of the wick forming a recess directly above the

wick provided with a line of perforations in its outer wall as shown at *g*. A flanged connection is made with an upper section *h* of the air distributer at the point *i* by bending over the upper edge of the skirt *a*, upon the flange *k* which forms the top of the recess above the wick as shown especially at *m*. The flange *k* is bent inwardly and slightly downwardly and is then bent vertically upward forming the upper perforated section *h* of the distributer. This construction provides in connection with the flared end of the skirt and its outwardly flared flange a restricted air passage to the perforations *g* and constitutes a very important part of the invention.

The usual and well known air distributing flanges *n*, *o*, are provided above the section *h*, these flanges being connected by a perforated wall *p*, of less diameter than the wall *h*.

We have found this construction to be very effective, there are no loose parts, and the particular configuration provides a very durable construction with a perfect distribution of air just where it is needed.

The drawing showing the invention represents a sectional view through the distributor and the wick tube of an oil stove.

What we claim is:—

An air distributer for wick stoves having an upper vertical cylindrical perforated portion and a lower cylindrical portion with an intervening hollow annular flange adapted to rest upon the top of the wick, the lower portion being adapted to fit within the central draft space of the stove and having a flared perforated portion adjacent said hollow flange, the inner surfaces of said upper and lower portions, including the flared portion and the hollow flange, defining the interior air space of the distributor.

In testimony whereof we affix our signatures.

FRED E. WHITE.
FREDERICK E. HOOPER.
